UNITED STATES PATENT OFFICE.

JOSEPH BALDA, OF NEWARK, OHIO, ASSIGNOR TO A. H. HEISEY & CO., OF NEWARK, OHIO.

DESIGN FOR A SHERBET OR SIMILAR ARTICLE.

Application filed May 8, 1920. Serial No. 379,986. Term of patent 3½ years.

To all whom it may concern:

Be it known that I, JOSEPH BALDA, a citizen of Hungary, residing at Newark, county of Licking, and State of Ohio, have invented a new, original, and ornamental Design for a Sherbet or Similar Article, of which the following is a specification.

I claim:

The ornamental design for a sherbet or similar article, substantially as shown.

JOSEPH BALDA.
